DESIGN FOR A JAR OR SIMILAR CONTAINER

Everett Worthington, Scarsdale, N. Y., assignor to American Can Company, New York, N. Y., a corporation of New Jersey

Application May 14, 1938, Serial No. 77,200

Term of patent 7 years

To the Commissioner of Patents:

Be it known that I, Everett Worthington, a citizen of the United States, residing at 15 Oak Lane, village of Scarsdale, county of Westchester, and State of New York, have invented a new, original, and ornamental Design for a Jar or Similar Container, of which the following is a specification, reference being had to the accompanying drawing, forming a part thereof.

The figure is a perspective view of a jar or similar container showing my new design.

I claim:

The ornamental design for a jar or similar container, as shown.

EVERETT WORTHINGTON.
